Patented Nov. 3, 1959

186,510

TOY TRAIN TRANSFORMER

Joseph L. Bonanno, South Orange, N.J., assignor to The Lionel Corporation, New York, N.Y., a corporation of New York

Application January 22, 1959, Serial No. 54,277

Term of patent 14 years

(Cl. D26—15)

Fig. 1 is a top plan view of a toy train transformer, showing my new design;

Fig. 2 is a front elevational view; and

Fig. 3 is a side elevational view, the opposite side being substantially a mirror image thereof.

I claim:

The ornamental design for a toy train transformer, as shown, and described.
